UNITED STATES PATENT OFFICE

SIDNEY Y. WHITE, OF NEW YORK, N. Y., ASSIGNOR, BY MESNE ASSIGNMENTS, TO RADIO CORPORATION OF AMERICA, OF NEW YORK, N. Y., A CORPORATION OF DELAWARE

RADIO RECEIVING SYSTEM

Application filed January 23, 1928. Serial No. 248,791.

This invention relates to radio receiving systems and sets in which the circuits used are adapted to be interchangeably connected with any type of antenna, including the highly capacitive elevated collector and the highly inductive loop or directional collector type. Heretofore circuits have not been arranged in such a way that either type of antenna may be connected without making some changes in the constants of the circuits in keeping with the more or less opposed electrical characteristics of the two types of collectors. The arrangement also adapts itself to the use of antennæ having different electrostatic and electromagnetic characteristics.

It is an object of this invention to provide a radio receiving system which may be interchangeably connected to any of the types of antennæ now common and well known without requiring alterations confusing to the unskilled operator.

Further and more definite objects will appear from the following specification, claims and drawing, in which the single figure represents a schematic diagram of my arrangement.

This drawing shows a circuit enclosed within the confines of a cabinet or other container indicated by the dotted line 1. Binding posts 2 and 3 may be located upon the cabinet 1 and interchangeably associated with the elevated antenna 5 and ground arrangement 6 or the loop or directional antenna 7. This interchangeability is indicated by simultaneously operable switches 8 and 9 connected by a suitable insulating linkage or other arrangement 10, indicated by the broken line, in such a way that in one position these switches will connect a loop 7 and in the other position the elevated antenna 5 and ground 6. Of course the switches may be dispensed with and connections made directly to the binding posts 2 and 3.

In order to permit this interchangeability the effects of the different types of antennæ

upon a circuit 12, as input to the translating device 13, in so far as the effects vary the selectivity or tuning of this circuit, must be kept low and uniform with frequency. This result, it has been found, can be obtained by utilizing what is commonly known as a combined electrostatic and electromagnetic coupling arrangement wherein different frequencies throughout a range of frequencies received are transmitted through this coupling with substantially uniform efficiencies. The coupling may be made more or less independent to suit the desired needs by connecting in the circuit the proper impedance 14 which has been found to act out satisfactorily when in the form of a small capacity. This also causes any antenna circuit connected to the input circuit 12 to be substantially detuned from the frequency band in which operating. This adjustment avoids the production of a resonant peak within the range of frequencies used which if had, would tend to make securing a substantially constant energy input practically impossible.

The combined coupling is composed of the electromagnetic coupling between coil 16, connected in series with the adjustable capacity 17 and the fixed capacity 18, and coil 21, and the electrostatic coupling across condenser 18. By selecting the polarity of the electromagnetic coupling to aid the electrostatic coupling, and selecting proper values of each kind of coupling, the combined coupling can be made to transfer energy in any desired way with frequency, such as keeping constant, and may be made as tight as desired and maintained so with frequency features more fully described in my copending application Serial Number 48936, filed August 8, 1925. The tighter this coupling the better will be the transmission of the effect of tuning the adjustable condenser 17 back onto the antenna circuit, and thus by utilizing a combined coupling as indicated a tight coupling can be maintained uniform-

ly effective for this purpose throughout a wide range of frequencies, as for instance, the broadcast range.

This arrangement permits having two terminals 2 and 3 on a radio cabinet 1, to which either the loop antenna 7 or the elevated electrostatic antenna 5 may be connected without making any alterations or change of adjustment in the receiver, and does not require any variable or other tuning element in the loop to obtain efficient results, as is the case with previously known loop arrangements. The terminals 2 and 3 being connected to a tunable circuit 16, 17 and 18 through the high impedance 14 and the combined coupling have been found suitable connections for any type of antenna. The energy is resonantly abstracted from either the elevated antenna or loop antenna by the selective circuit 16, 17, 18, which has an effect equivalent to tuning the antenna circuit, thus making special tuning for these circuits unnecessary.

The translating device 13 may be in the form of a vacuum tube or any other energy transfer arrangement. A source of high potential may be applied to the terminals 23 and the output of the device taken off at 24 in any desired way.

It is not intended to be limited to the exact arrangements shown for considerable departure therefrom is possible without departing from the spirit and scope of the invention. The various elements of the circuit may be made adjustable both as to coupling or electrical values. Equivalent elements may be substituted for those shown.

It is intended to be limited only to the extent indicated in the following claims.

40 I claim:

1. A radio receiver input system including a loop collector, a translating system, a circuit tunable through a wide range of frequencies connected across said translating system, a combined electrostatic and electromagnetic input coupling poled to transfer energy in phase to said circuit, said electromagnetic coupling being less than 100 per cent, and a high impedance capacity connection between the terminals of said collector and the terminals of said coupling.

2. A radio receiver input system including a loop collector, a translating system, a circuit tunable through a wide range of frequencies connected across said translating system, a combined electrostatic and electromagnetic input coupling poled to transfer energy in phase to said circuit, the circuit of said loop collector being completed through said coupling, and impedance means in said completed loop circuit so chosen as to prevent said loop circuit from becoming resonant at any frequency within the oper-

ating range of frequencies of said tunable circuit.

3. In a radio receiving system, the combination of a loop collector, a translating device having a resonant input circuit, a combined electrostatic and electro-magnetic coupling between said loop and said resonant circuit so poled as to transfer energy electrostatically and electromagnetically in phase from said loop to said resonant circuit, said electrostatic coupling forming a portion of said resonant circuit and means for isolating the tuning effects in said resonant circuit from said loop collector.

4. In a radio receiving system, the combination of a collector, a translating device having a resonant input circuit tunable to incoming signal frequencies, a combined electrostatic and electromagnetic coupling between said collector and said resonant circuit so poled as to transfer energy electrostatically and electromagnetically in phase from said collector to said resonant circuit, and so related that the combined electromagnetic and electrostatic transfer of energy is substantially constant throughout the frequency range of said resonant circuit, and means for isolating the tuning effects in said resonant circuit from said collector, whereby said collector is rendered substantially aperiodic throughout the frequency range of said resonant circuit.

5. In a radio receiver input system, the combination of an untuned loop collector, a translating system, a circuit tunable through a wide range of frequencies connected across said translating system, an input coupling to said circuit including means for transferring energy increasingly with decrease of current frequency and means for transferring energy in phase with said first transfer means decreasingly with decrease of current frequency, and high impedance capacity means completing the circuit of said loop collector through said coupling means.

6. In a radio receiver input system, the combination of a collector, a translating system, a circuit tunable through a wide range of incoming signal frequencies connected across said translating system, means for transferring energy from said collector to said circuit increasingly with increase of current frequency, means for transferring energy from said collector to said circuit decreasingly with increase of current frequency, said transfer means being poled to transfer energy in phase accord and adjusted to transfer energy at substantially the same rates throughout their reversed energy transfer-frequency characteristics, and means materially isolating the tuning effects in said circuit from said collector.

7. In a radio signalling system, an antenna system having two terminals, a translating device, a circuit tunable through a

range of incoming signal frequencies coupled to said translating device, a combined electrostatic and electromagnetic coupling poled to transfer energy in aiding phase to 5 said tunable circuit, said electrostatic coupling forming a portion of the tuning means of said tunable circuit and also a path for current flowing between said terminals and a connection between said antenna terminals and said coupling whereby energy is 10 transferred at substantially uniform efficiency through said coupling at the several frequencies over which said first named circuit is tunable.

15 In testimony whereof I affix my signature.
